UNITED STATES PATENT OFFICE.

THOMAS F. KENNEDY, OF BOSTON, MASSACHUSETTS.

TIE.

Application filed April 4, 1924. Serial No. 704,238.

To all whom it may concern:

Be it known that I, THOMAS F. KENNEDY, a citizen of the United States, residing at Boston, in the county of Suffolk and State 5 of Massachusetts, have invented new and useful Improvements in Ties, of which the following is a specification.

This invention relates to a tie for rail-ways, the general object of the invention be-10 ing to make the tie of metal and to so form it that it will be held against movement in the road bed.

Another object of the invention is to pro-15 vide clamping means for clamping the rails to the tie.

This invention also consists in certain other features of construction and in the combination and arrangement of the several parts, to be hereinafter fully described, 20 illustrated in the accompanying drawings and specifically pointed out in the appended claims.

In describing my invention in detail, ref-25 erence will be had to the accompanying drawings wherein like characters denote like or corresponding parts throughout the sev-eral views, and in which:—

Figure 1 is a plan view of a portion of a 30 railroad track showing my invention in use.

Figure 2 is a transverse sectional view through the track.

Figure 3 is a section on line 3—3 of Fig-ure 1.

Figure 4 is a section on line 4—4 of Fig-ure 1.

Figure 5 is a section on line 5—5 of Fig-ure 3.

Figure 6 is an enlarged sectional detail 40 view through one end of a tie.

Figure 7 is a perspective view of one of the rods 10.

In these views, 1 indicates the rails and 2 the improved ties. These ties are formed of metal and are of hollow construction and of 45 rectangular shape in cross section. Recesses 3 are formed in the bottom of each tie, each recess beginning at a point adjacent the center and extending to a point adjacent the end of the tie and each recess is of concave 50 shape and gradually tapers off towards its outer end. These recesses form suction spaces for holding the tie against movement in the track bed and each end of the tie is shaped to form a wedge 4 which acts to prevent 55 longitudinal movement of the tie in the ballast. The ties are provided with the ribs

5 for receiving the rails between them and the rails are clamped to the ties by the jaw members 6 which are pivotally mounted within the ties by the pivot pins 7 and 60 which extend through slots 8 in the ties and have their horizontal jaw parts 9 arranged to engage the bases of the rails. These jaw members are actuated by the rods 10 which pass through the ends of the ties, the pro-65 jecting end of each rod being provided with a hinged handle 11 and with a spring 12 which acts to hold the jaws in gripping po-sition. Each rod 10 is provided with a pair 70 of eyes, one eye receiving a jaw of one pair of jaw members and the other eye a jaw of the other pair of members so that when the rod is moved a jaw of each pair of jaw mem-bers will be moved in unison. The spring 12 bears against an enlargement on the rod 75 and a part on the tie and tends to press the rod outwardly and thus hold the parts nor-mally in a position with the jaws in grip-80 ping position. Latch members 13 are also provided on the ties for engaging some of the jaw members.

From the foregoing it will be seen that I have provided a simple and inexpensive metal tie which will be firmly held in place by the ballast and which is provided with 85 clamping means for the rails so that a rail-way can be put down very quickly and there is no danger of the rails becoming loosened from the ties.

The handles are made of hard wood so 90 that they will last for a long time and they may be provided with a ring lock to hold them in locked position. By making the tie of metal there is no danger of them be-ing destroyed by fire nor floating away in 95 floods and it will be very useful in use on trestles and bridges.

It is thought from the foregoing descrip-tion that the advantages and novel features 100 of my invention will be readily apparent.

I desire it to be understood that I may make changes in the construction and in the combination and arrangement of the several parts, provided that such changes fall with-in the scope of the appended claims.

What I claim is:—

1. A railroad tie formed of metal and having ribs on its upper face, the ribs being arranged in pairs with each pair forming a rail receiving space, two pairs of jaw mem-bers pivoted in the tie and passing through 110 the upper face thereof for engaging the

- bases of the rails, rods movably mounted in the tie and having their ends passing from the ends of the same, each rod being connected with a jaw member of each pair of 5 jaw members, springs on the rods for normally holding the rods in a position with the jaw members gripping the rails and handles on the outer ends of the rods for adjusting the same.
- 10 2. A railroad tie formed of metal and having ribs on its upper face, the ribs being arranged in pairs with each pair forming a rail receiving space, two pairs of jaw members pivoted in the tie and passing

through the upper face thereof for engaging the bases of the rails, rods movably mounted in the tie and having their ends passing from the ends of the same, each rod being connected with a jaw member of each pair of jaw members, springs on the rods for normally holding the rods in a position with the jaw members gripping the rails, handles on the outer ends of the rods for adjusting the same, and latch means on the upper face of the tie for holding the jaw members in closed position.

In testimony whereof I affix my signature.
THOMAS F. KENNEDY.
